UNITED STATES PATENT OFFICE.

GEORGE HOFFMAN, OF FONTANET, INDIANA.

LOADING DEVICE FOR LOCOMOTIVES.

SPECIFICATION forming part of Letters Patent No. 707,927, dated August 26, 1902.

Application filed May 1, 1902. Serial No. 105,512. (No model.)

To all whom it may concern:

Be it known that I, GEORGE HOFFMAN, of Fontanet, in the county of Vigo and State of Indiana, have invented a new and useful Improvement in Coaling Devices for Locomotives, of which the following is a specification.

My invention is in the nature of a simple, cheap, durable, and efficient device for transferring coal from any elevated storage-place to the tender of a locomotive in an expeditious manner and with a great saving of labor.

It relates to that form of coaling device in which a movable bin or carrier is mounted upon the upper end of a tilting frame fulcrumed upon its lower end and adapted to receive its charge of coal and then to swing forwardly and downwardly to discharge its load into the tender; and it consists in various features of construction and arrangement of parts for balancing and regulating the movement of the carrier and its contents, as will be hereinafter fully described with reference to the drawings, in which—

Figure 1 is a side elevation of the apparatus, showing in dotted lines its position for receiving the coal and in full lines the position for discharging the coal. Fig. 2 is a plan view on a larger scale; Fig. 3, a front view, and Fig. 4 a detail view of the end of the carrier.

In the drawings, A represents any suitable framework, mounted upon sills and strongly braced and carrying at its upper end a horizontal shaft B.

C is the carrier or movable bin, which is made of any suitable capacity and is designed to receive the coal from an elevated point either direct from the cars or from a chute and to transfer it in regulated quantities to the locomotive-tender. This carrier-bin has at each end a trunnion c, journaled in a bearing carried on the top of a vertical strut-frame D, composed of side bars connected by cross bars and braces, the side bars of which are pivoted or hinged at their lower ends upon substantial metal bearings d on a cross-sill d'. One side of the carrier-bin is also connected by means of a hinge-joint e to the top of a long vertical strut-bar E, which in turn is pivoted or hinged at its lower end upon substantial metal bearings e', mounted upon a cross-sill

e² at a somewhat-higher point than the bearings of the strut-frame D. The difference in the levels of the lower fulcrum of the strut-frame D and strut-bar E should correspond to the different levels of the hinge-points of the upper ends of these members with the carrier-bin. This gives when the bin is swung over to the dotted position a parallel motion to these parts that holds the carrier-bin vertical through its swinging movement and avoids any tilting or spilling of its contents. When the carrier-bin is over the tender, its load of coal is dumped into the tender by two trap-doors F F, forming the bottom of the bin, which doors are simultaneously released to allow the contents to fall. These trap-doors are held closed by spring-hinges f f and close together in the middle automatically after the coal drops. Projecting from the ends of these doors are two coinciding lugs l l', which are caught and held up against the weight of the coal by a hook-bolt b, attached to a slide b', held in keepers b² b² and connected by a short rod b³ with a crank-arm G at each end of a rock-shaft G', the crank-arm being normally held down with the hook-bolt b, engaged with the lugs l l', by a counterweight H on the crank-shaft. When the load is to be dumped, this counterweight is lifted automatically by contact of the arm G with block x on the frame D to withdraw the hook-bolt, and the coal then forces open the spring-hinged doors, which immediately close again after the load is discharged, the lugs of the doors forcing back the beveled faces of the hook-bolt and locking again. To regulate the descent of the carrier-bin, I provide a special arrangement of balancing device. It will be understood that when the tilting frame, which supports the carrier-bin, is vertical the load of the bin exerts but little leverage on the frame; but when the frame is swung out to the inclined dumping position, as indicated in the full lines of Fig. 1, the leverage constantly increases as the frame moves out. To compensate for this and at the same time to use the smallest amount of balancing-weight, I attach to each end of the bin a wire cable g, which is extended to and around cone-shaped drums K on the shaft, which drums have spiral grooves to receive the cables g and which grooves run

from the outer periphery of the cone to a point near the center, and the cables are so wound upon these drums that when the carrier-frame is vertical the cable is on the part of the groove 5 of largest diameter, and when the carrier-frame is at its outwardly-inclined position, where the leverage of the load is greatest, the cable rests on the part of the drum near the center. I also place on the same shaft a rigidly-attached drum J, on which is formed a similar spiral groove, and on this groove is wound a cable h, which passes over small pulleys i on the top of the stationary frame and then descends and is attached to a balance-weight K', guided by keepers at o o on a fixed vertical bar M. This cable h, however, is wound on its conical drum reversely to that of the cable g—that is to say, when the carrier-frame is vertical the cable h is resting on the smaller periphery of the drum, and when the carrier-frame is extended the cable is resting on the larger periphery of its drum, so that the pull of the weight is exerting its greatest leverage. By this arrangement of the two cables and conical drums the increased leverage of the carrier-frame when extended is compensated for by a very small balancing-weight, as the leverage of the two drums is compounded. By such arrangement the carrier-bin 25 when loaded will upon the release of the strap-brake move easily and gently outward without jar or concussion, raising the weight as it moves outward, and after the load is dumped the balance-weight brings back the bin with a constantly-diminishing leverage, that also avoids all jar on the return movement. To regulate the movement of the carrier, a strap-brake N surrounds the drum and lies in a groove of the same and is tightened 35 thereupon by a hand-lever O and a keeper with pin P.

I am aware that it is not broadly new to provide a coal-carrier mounted upon the top of a tilting frame, which carrier also tilts to discharge the load, and I make no claim to this. I am also aware that a parallel-motion transferring device is not new, and I do not claim this broadly.

Having thus described my invention, what

I claim as new, and desire to secure by Letters Patent, is—

1. A transferring apparatus comprising a carrier, a tilting frame supporting the carrier at its upper end, a conical compensating drum and a cable connecting the carrier mechanism to the said drum and resting on the smaller circumference of the cone when the frame is extended as described.

2. A transferring apparatus comprising a carrier, a tilting frame supporting the carrier at its upper end, a conical compensating drum, a cable connecting the carrier mechanism to the said drum and resting on the smaller circumference of the cone when the frame is extended, a second conical drum rigidly connected to the first-named drum, and a weight and cable passing around said second conical drum and resting on the larger circumference of the drum when the frame is extended substantially as described.

3. A transferring apparatus comprising a carrier, a tilting frame supporting the carrier at its upper end, a horizontal shaft bearing a pair of conical compensating drums with spiral grooves, cables connecting the same to the carrier mechanism, and another conical compensating drum with cable wound reversely to the first-named and having attached thereto a balance-weight substantially as and for the purpose described.

4. The combination with the carrier and its tilting frame; of grooved and conical compensating drum with cable and weight, and a strap-brake embracing and lying inside the groove in said drum substantially as and for the purpose described.

5. The combination with the carrier and its parallel-motion supporting-frame; of spring-hinged trap-doors for the carrier having extended lugs at the ends, a bevel-faced hook-bolt, a rock-shaft with weighted crank-arm, and a rod connecting the crank-arm to its hook-bolt substantially as shown and described.

GEORGE HOFFMAN.
